UNITED STATES PATENT OFFICE

93,252

DESIGN FOR A BOAT

Carl Henry Stratton and Myrtle Stratton, Oklahoma City, Okla.

Application May 12, 1934, Serial No. 51,771

Term of patent 7 years

To all whom it may concern:

Be it known that we, CARL HENRY STRATTON and MYRTLE STRATTON, citizens of the United States, residing at Oklahoma City, in the county of Oklahoma and State of Oklahoma, have invented a new, original, and ornamental Design for a Boat, of which the following is a specification, reference being had to the accompanying drawings, forming part thereof.

Figure 1 is a view in side elevation of a boat, showing our new design.

Figure 2 is a top plan view thereof.

Figure 3 is an end elevational view, looking at the bow of the boat.

Figure 4 is an end elevational view, looking at the stern of the boat.

We claim:—

The ornamental design for a boat as shown.

CARL HENRY STRATTON.

MYRTLE STRATTON.
